CLAIM

The ornamental design for a stringed musical instrument, as shown and described.

DESCRIPTION

FIG. 1 is a front perspective view of a stringed musical instrument showing my new design; FIG. 2 is a rear perspective view of a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

Any broken lines, including small and large dashed lines, showing portions of the design are for illustrative purposes only and form no part of the claimed design. The evenly spaced broken lines represent the portions of the stringed musical instrument that form no part of the claimed design.
